UNITED STATES PATENT OFFICE

2,619,394

LATCH CONNECTOR FOR SECTIONAL
TABLE TOPS

Julius A. Mahr, Minneapolis, Minn.

Application October 20, 1949, Serial No. 122,471

2 Claims. (Cl. 311—4)

1

My present invention relates to improvements in tables and more particularly to a latch mechanism for connecting two or more tables to form a single table comprising detachably connected table sections.

While the invention is intended for general use to detachably connect tables having rectangular tops, it is especially well adapted for connecting tables of the type disclosed and broadly claimed in my pending application for United States Letters Patent filed November 5, 1948, under Serial No. 58,424.

The object of this invention is to provide a novel mechanism for rigidly and detachably connecting two or more tables end to end, side by side, or end to side, so that the tops thereof are smooth and in the same plane without gaps there-between.

To the above end, the invention consists of the novel devices and combination of devices, herein-after described and defined in the claims.

In the accompanying drawings, which illustrate the invention, like characters indicate like parts throughout the several views.

Referring to the drawings:

Fig. 1 is a view partly in side elevation and partly in longitudinal, substantially central section, showing two tables detachably connected end to end by two of my improved latches, and also showing at the outer end of the tables, on each side thereof, one of the units of one of the latches;

Fig. 2 is a bottom plan view of the table tops, as shown in Fig. 1, with the leg frames sectioned on the line 2—2 of Fig. 1;

Fig. 3 is a fragmentary view of the invention as shown in Fig. 2, on an enlarged scale;

Fig. 4 is a fragmentary detail view partly in elevation and partly in section taken on the line 4—4 of Fig. 3 and turned right side up, on an enlarged scale;

Fig. 5 is a fragmentary detail view principally in section, taken on the line 5—5 of Fig. 3, on an enlarged scale;

Fig. 6 is a bottom plan view showing two tables connected side by side, some parts being removed; and

Fig. 7 is a view corresponding to Fig. 8, except that the tables are connected end to side.

In Figs. 6 and 7 of the drawings, there is shown two tables 5, each having folding leg frames 6 identical with the leg frames shown in the pending application for Letters Patent heretofore referred to.

Each table 5 has a rectangular top 7 which rests 55 secured to the table tops 7 by screws, not shown.

2

on a rectangular frame 8 made of side angle bars 9, and end angle bars 10. The frame 8 further includes a pair of laterally spaced cross-tie angle bars 11 rigidly secured at their ends to the side bars 9. The table top 7 is secured to the frame 8 by a plurality of clips 12 which overlap the horizontal flanges of the angle bars 9, 10 and 11. These clips 12 are secured by screws 13 to the table top 7. The leg frames 6 are pivoted to the angle bars 11, as indicated at 14. It is important to note that the vertical flanges of the end angle bars 10 are turned downwardly, and their outer faces are flush with the end edges of the table top 7.

15 The latch mechanism includes, at each end of the frame 8, a cam finger 15, and a lever 16 having near its outer end portion, a shoulder 17. The cam finger 15 is rigidly secured to one of the side angle bars 9 and extends outwardly thereof under the table top 7. The lever 16 is pivoted to an outwardly projecting ear 18 rigidly secured to the other side angle bar 9 for swinging movement in the plane of the frame 8. The lever 16 outwardly of its shoulder 17 is upwardly inclined to afford a hand hold 19 by which the lever may be manipulated. As shown in Figs. 2 and 3, the two cam fingers 15 and the two levers 16, at the abutting ends of the two tables 5, are diagonally opposite each other so that there is a cam finger 15 and a lever 16 on each side of the table tops 7. By swinging the levers 16 toward the cam fingers 15, they pass thereunder and their shoulders 17 engage the convex back edges of the cam fingers 15 and draw the two table tops 7 toward each other and clamp the adjacent ends thereof and the respective end angle bars 8 together.

In addition to the cam fingers 15 and levers 16, the two table tops 7 are further detachably connected by dowel pins 20. One of these dowel pins 20 is secured to the downturned flange of each end angle bar 10 on each table top 7 and projects outwardly thereof. The dowel pins 20 on adjacent ends of the two table tops 7 extend through holes 21 in the downturned flanges of the end angle bars 10, Figs. 2 and 3. Obviously, the dowel pins 20 positively hold the two table tops 7 against relative movement in all directions except endwise movement to separate said table tops. The two dowel pins 20 on adjacent ends of the table tops 7 are diagonally opposite one another.

In some types of tables, the rectangular frame may be dispensed with and in lieu thereof, only end angle bars, and short side angle bars are used, secured to the table tops 7 by screws, not shown.

It is evident that any number of tables may be connected end to end, side to side, or end to side to form a single table.

Referring now to the arrangement of the tables as shown in Figs. 6 and 7, wherein parts that correspond to like parts in Figs. 1 to 5, inclusive, are given the same reference numerals followed by a prime ('):

In Fig. 2, the table tops 7 can only be connected end to end and in order that the table tops can be connected side by side, as shown in Figs. 6 and 7, or end to side in addition to being connected end to end, there is added to the frame 8' of each table top 7' an extension 22 on each side thereof. Each frame extension 22 is formed by an angle bar and includes a longitudinal member 23 and inturned members 24. The down-turned flanges of the longitudinal members 23 are flush with the longitudinal edges of the table tops 7' and the inturned members 24 extend to the frame side angle bars 9'. To the inturned members 24 of each frame extension 22 are secured to the one a cam finger 25 and to the other a lever 26. The cam fingers 25 and the lever 26 are identical with cam fingers 15 and the levers 16.

To connect the two table tops 7' side by side, as shown in Fig. 6, the cam fingers 25 and the levers 26 on the adjacent sides of the table tops 7' are used. In connecting the two table tops 7', as shown in Fig. 7, wherein one end of one of one of the table tops 7' is connected to one of the sides of the other table top 7', a combination of the cam fingers 15'-25 and levers 16'-26 is used.

The dowel pins on the longitudinal member 23 are designated by the numeral 28. It is not thought necessary to show the holes in the longitudinal member 23 for the dowel pins 28.

The drawings illustrate a commercial form of the invention, but it will be understood that the invention described is capable of certain modifications as to details of construction and arrangement of parts within the scope of the invention herein disclosed.

What I claim is:

1. Two tables having rectangular tops, a pair of latches connecting the tables with their tops in edgewise abutting engagement, said latches being under the table tops and spanning the joint therebetween, said latches including a pair of cam fingers that extend in opposite directions transversely of the tables and fixed at their inner ends one relative to each table top, said cam fingers except at their fixed ends being spaced below the table tops and parallel thereto, the

back edges of the cam fingers being curved outwardly toward said joint and affording cams, said latches further including a pair of ears fixed, one relative to each table top opposite the cam fingers, and a pair of levers pivoted one to each ear for swinging movement between the table tops and the cam fingers, the levers at their outer end portions being downwardly offset to afford shoulders engageable with the cams during swinging of the levers over the cam fingers to draw the tables toward each other, the offset end portions of the levers outwardly of the shoulders affording hand holds.

2. Two substantially duplicate tables, each including a rectangular frame formed of two side and two end angle bars, one of the flanges of each side angle bars being turned outwardly and the other downwardly, one of the flanges of each end angle bar being turned inwardly and the other downwardly, a table top on each of the frames and secured thereto, said table top extending outwardly of the frame side bars, the ends of each table top being flush with the outer faces of the down-turned flanges of the end angle bars, and a pair of latches connecting the two tables in endwise abutting engagement, each latch including an ear, a lever pivoted at one end portion to the ear and a cam finger having a convex edge, the outer end portion of the lever being bent downwardly to afford a shoulder engageable with the convex edge of the cam finger, said lever outwardly of its shoulder being bent upwardly, each side bar having at one end portion one of the ears and at its other end portion one of the cam fingers, the ears and the cam fingers on each of the two side bars being in reverse order, the ears and the cam fingers being secured to the out-turned flanges of the side bars on the under sides thereof and projecting outwardly thereof, said levers being between the ears and the table top and the levers, when in engagement with the cam fingers, being between said fingers and the table top.

JULIUS A. MAHR.
